UNITED STATES PATENT OFFICE.

OTTO M. STIEHL, OF ST. LOUIS, MISSOURI.

KNOCKDOWN RECEPTACLE.

949,204.

Specification of Letters Patent. Patented Feb. 15, 1910.

Application filed February 5, 1909. Serial No. 476,733.

To all whom it may concern:

Be it known that I, OTTO M. STIEHL, a citizen of the United States, residing at St. Louis, in the county of St. Louis City and State of Missouri, have invented a new and useful Knockdown Receptacle, of which the following is a specification.

This invention relates to packing and shipping boxes of that type designed to be collapsed or knocked down so as to occupy the minimum space when not in use, and thus materially reduce the cost of transporting empty crates or boxes.

The object of the invention is to provide a box of this type formed of separate parts each of which is preferably stamped of sheet metal, all of the parts being so shaped as to slidably engage one another in such a manner as to hold the parts securely against displacement in any direction, it merely being necessary to utilize a wire or other sealing device for preventing the box from being accidentally opened, or from being opened by unauthorized persons without detection.

25 A further object is to provide a box of this type the parts of which can be securely held together when the box is collapsed.

With these and other objects in view the invention consists of certain novel details of 30 construction and combinations of parts hereinafter more fully described and pointed out in the claims.

In the accompanying drawings the preferred form of the invention has been shown.

35 In said drawings:—Figure 1 is a perspective view of the box set up for use. Fig. 2 is a similar view, showing the box collapsed, a portion of one wall of the box being broken away and the cover being shown partly removed. Fig. 3 is a vertical section through one portion of the box when set up. Fig. 4 is a horizontal section through the interengaging portion of one end and one side panel. Fig. 5 is a transverse section through 45 the box set up for use. Fig. 6 is a view showing in perspective the rear panel, one end panel, and the top and bottom panels of the box, all of said panels being separated.

Referring to the figures by characters of 50 reference 1 designates the base panel of the box, the same being provided at its front and rear edges with upstanding flanges 2, each having an outwardly and downwardly bent edge portion forming an inverted channel 55 as indicated at 3, the outwardly extending

portion of the front flange 2 being formed with an opening 4 at a point preferably midway between the ends of the flange 2. Upstanding flanges 5 are formed at the ends of panel 1, each of these flanges being folded upon itself to form an inner longitudinally extending engaging portion or leaf 6 and the folded portions of the flange being bent outwardly and downwardly as indicated at 7 to form a retaining ledge in the form of an inverted channel. It is of course to be understood that this base panel and all of the flanges mentioned are formed in a single sheet of metal, preferably galvanized iron, and of sufficient strength to resist the ordinary rough usage to which it might be subjected. Each end panel 8 of the box is likewise formed of metal and is provided at its side edges with flanges 9, each of which is folded longitudinally to form a channeled 75 engaging member for the purpose herein-after set forth. The lower edge portion of the panel 8 is folded upon the outer face of the panel to form a leaf 10, while the upper portion of each end panel is folded outwardly and downwardly upon said panel to form an inverted channel 11 constituting a guide as hereinafter set forth.

The front and rear panels of the box are similar in construction, each being formed 85 of a single sheet of metal and having marginal flanges for the purpose of engaging corresponding portions of adjoining panels. Each of these panels, which has been indicated at 12, is provided at its ends with engaging flanges 13 folded over the face of the panel, while arranged along the upper longitudinal edge of said panel is an outwardly and downwardly bent retaining flange 14. The flange 14 of the rear panel is preferably 95 extended inwardly against said panel as shown at 15 in Fig. 5, while the other flange 14 has an opening 16 in its end similar to the opening 4 heretofore referred to.

The top panel is formed in a single sheet 100 of metal and extending from the ends of this panel are downwardly and inwardly extending channeled guide members 18 while a stop flange 19 extends downwardly from the rear edge of the panel and has a longitudinal extension 20 extending inwardly from its lower edge and designed to extend under and engage the retaining portion 14 of the rear panel 12. The front of the box cover is open and an opening 21 is formed in the 110

cover adjacent the front edge thereof and is designed, when the box is closed, to register with the opening 16 if the box is set up, and with the opening 4 when the box is collapsed.

5 When it is desired to set up the box constituting the present invention the bottom panel 1 is placed with its flanges 2 and 5 extending upwardly, and the end panels 8 are then inserted into the spaces formed between the ends of flanges 2 and 5, said spaces being indicated at 22 and being produced by shortening the flanges 2. When the end panels 8 are thus located their leaves 10 are inserted between the flanges 5 and the leaves 6 15 and said end panels are then shifted longitudinally until their guide portions 9 become seated within the spaces 22. The front and rear panels 12 are then placed with their guide members 13 in engagement with the guide members 9, after which said front and rear panels are pushed downwardly so as to bring their lower edges between the flanges 2. The bottom and wall panels are thus rigidly held with relation to one another, and, 25 when it is desired to close the box thus formed, the top panel 17 is placed with its guide members 18 in engagement with the guide members 11 of the end panels 8. Said top panel 17 is then shifted toward the front 30 until its stop flange 19 is brought into contact with the retaining flange 14. When the panel 18 assumes this position the opening 21 is brought into register with the opening 16 whereupon a sealing wire 23 may be inserted through said openings and its end portions secured together in any preferred manner.

When it is desired to collapse the box the foregoing operation is reversed and the 40 front and rear panels 12 are then placed one above the other upon the bottom panel 1 and the end panels 8 are then placed side by side above the panels 12. This arrangement has been indicated in Fig. 2. After 45 the parts have thus been assembled the top panel 17 is placed with its guide portions 18 in engagement with the guides 7 on the flanges 5, after which the top panel is slid into position upon the flanges of the bottom 50 panel, thus bringing the opening 21 into register with the opening 4 and permitting the insertion of a sealing wire or the like through said openings. When the parts are thus assembled the box can be stored in a 55 comparatively small space and there is no danger of any part thereof becoming misplaced.

As heretofore pointed out all of the panels and the parts connected thereto are preferably formed of sheet metal which may be galvanized for the purpose of protecting it from the action of moisture etc. The entire device is formed of but six parts, to wit: the front and rear panels, the end panels 65 and the top and bottom panels, and the

means utilized for holding these panels together are integral with the respective panels, so that the device is always ready to be either assembled or knocked down.

Obviously various changes may be made in the construction and arrangement of the parts without departing from the spirit or sacrificing the advantages of the invention.

What is claimed is:

1. A knock-down receptacle comprising a 75 base panel having oppositely disposed flanges or retaining devices, a retaining leaf extending over the inner face of each flange, a combined guiding and retaining member extending over the outer face of each flange, 80 end panels detachably engaging said leaves, said panels having outstanding guiding and engaging portions, front and rear panels slidably engaging the end panels, and a top panel having channeled guide devices 85 slidably and detachably engaging the retaining devices of either the end panels or the bottom panel.

2. A knock-down receptacle comprising a base panel having end flanges, retaining 90 leaves integral with and extending over the inner faces of said flanges, guide devices upon the outer faces of said flanges, end panels detachably engaging and retained by said leaves, guide devices carried by the end 95 panels, front and rear panels slidably and removably engaging the end panels, and a top panel having guide devices slidably and detachably engaging the guide devices of either the end panels or the bottom panel. 10

3. A knock-down receptacle comprising a base panel having upstanding marginal flanges provided with inner engaging portions and outer channeled retaining ledges, end panels slidably engaging the inner engaging portions and having outer channeled guides, front and rear panels interposed between and slidably engaging the end panels, and a top panel having channeled guide members slidably into engagement with and retained by the guides of the end panels when the box is set up, and by the retaining ledges of the bottom panel when the receptacle is collapsed.

4. A knock-down receptacle comprising a 115 bottom panel formed of sheet metal and having marginal flanges, two of the opposed flanges being folded longitudinally to form an interior retaining leaf and an exterior 120 guide member, sheet metal end panels having integral retaining leaves for engagement with the leaves of the bottom panel, there being guiding members upon the end panels, sheet metal front and rear panels slidably 125 engaging the end panels and extending between the flanges on the base panel, and a top panel formed of sheet metal and having guide members for slidably engaging the guide members on the end panels when the receptacle is set up, and for slidably engag- 130

ing the guide members on the folded flanges of the base panel when the receptacle is collapsed.

5. A knock-down receptacle formed of sheet metal and comprising a base panel having upstanding marginal front, rear and end flanges, the end flanges being folded longitudinally to constitute interior retaining leaves and exterior guide devices, the said 10 end flanges being spaced from the front and rear flanges, end panels insertible transversely of the bottom panel into engagement with the retaining leaves, said end panels having top guides and front and rear inwardly folded guide flanges, front and rear panels having end flanges lapping the outer faces thereof and slidable into engagement

with the guide flanges of the end panels, a top panel, and means upon the top panel for detachably engaging the top guides on the 20 end panels to hold said top panel in position above the front and rear panels when the receptacle is set up, said top panel being 25 slidable into engagement with the guide devices of the bottom panel when the receptacle is collapsed.

In testimony that I claim the foregoing as my own, I have hereto affixed my signature in the presence of two witnesses:

OTTO M. STIEHL.
